MEANS FOR ELIMINATING DIVIDED MATERIAL IN INDUSTRIAL PROCESSES

John F. Roche, Jr., Oak Park, and George A. Harker, Chicago, Ill., assignors to Binks Manufacturing Company, Chicago, Ill., a corporation of Delaware

Application June 11, 1938, Serial No. 213,174

2 Claims. (Cl. 261—112)

The present invention relates generally to the elimination of particles, such as dust or fume, from coating processes, or the like, held in suspension or carried in the air or other fluids, so as to free the latter from such foreign matter. The embodiment chosen to illustrate the invention is shown for elimination of fume in connection with spray booths of the type wherein objects and articles to be coated are sprayed with coating material, usually by spray guns, and wherein there is a passage of air to carry away the fumes and other matter projected past or deflected from the object toward which the spray is directed, also wherein means are provided for the effective and economical reclaiming of the coating material particles that might otherwise be lost or wasted; and further wherein the air is cleansed so that no foreign matter will be discharged in the atmosphere with the outgoing air.

The device disclosed is used preferably for the elimination of fumes produced from the use of pigments, paints, lacquers, vitreous enamels, mixtures of water or other liquids and non-soluble ground material, such as silicon oxides, ceramic materials, etc., by the washing down of the particles with a liquid, such as water, oil, or the like, and the invention comprehends the elimination of both the material and the water or other liquid from the air or other fluid passing from the means where the material is sprayed and the fume is formed, it being understood, however, that while the illustrative embodiment is disclosed in a coating process, the invention is capable of other uses in the industrial arts, wherein foreign matter in the form of suspended particles of dust, fume, or the like, forms or otherwise arises and is carried by the air, or other fluids, to effect an elimination of the foreign matter, as by a washing down and collecting of the foreign matter so as to free the air or other fluid therefrom.

Spray material of the kind mentioned usually adheres to the surfaces contacted by the material, especially to the surfaces of the plates of the air cleaning means, such as filters, eliminators, etc., and soon clogs up the device. This is especially true in devices of the dry cleaning type, and also in those where there is a mere wetting of the surfaces, or an inadequate flow of the liquid, as water, used to clean the air.

By the present invention there is an ample washing, or rather a flushing or flooding of the surfaces with which the fume material would contact or impinge whereby the surfaces, as of

the cleaning plates, are constantly maintained neat and clean, thus preventing any clogging of the air cleaning means, and avoiding shutdowns that would otherwise be required because of clogging. One of the objects of the invention is, therefore, to operate the device continuously without any interruption, and still maintain the neat and clean conditions mentioned. A flooding action is obtained instead of an atomizing or spraying action as heretofore. In this way there is a constant and continuous washing or flooding off of the pigments or other particles that would otherwise adhere to or accumulate upon the surfaces, such as the surfaces of the plates of the cleaning or eliminating device. The particles are caught in the film or stratum of liquid moving over the surface and are prevented from sticking or settling in place. Thus, it will be seen that the present invention is, in nature, a washing down of the fume particles in a dry type filter with a flushing or flooding liquid.

It will, of course, be understood that while water has been referred to, by way of illustration, as the cleaning or washing fluid, other fluids may be used, such as oil and other liquids. It is preferable to so treat the liquid as to be "soft," that is, slightly alkaline, so as to reduce the tendency of the particles to adhere or otherwise stick to the surface mentioned.

In spray booths of this type there is usually provided a spray compartment in which the spraying operation occurs by directing the sprayed coating material upon the object or article to be coated, also located in the compartment. The compartment is open at the front for inflow of air which passes by the operator and the object, for passage of the air to the rear of the compartment into an air washing chamber where the air is cleaned of suspended particles, etc.

At the rear of the compartment is usually a generally upright wall or apron over the front face of which flows down a sheet of water or other liquid for washing off or flushing of the fume particles or spray material that may have been projected against the apron, the flush water with the particles dropping from the lower end of the apron into the path of the air passing from the compartment to the air washing chamber so that there is a preliminary washing of the fume-bearing air by the flushing water from the apron. The water may drop in a receptacle where the particles may settle and be reclaimed. It is also usual to have suitable means at the upper end of the apron for supplying the flush-

ing liquid thereto as in the form of a sheet of water flowing down over the face of the apron.

Among the objects of the invention is to provide in connection with a spray booth of the character referred to, or any other device or means used in the industrial arts wherein dust, fume, or the like is formed in any manner, whether from a spraying process or otherwise, a novel means comprising an air cleaning device 10 in the air cleaning chamber communicating at its lower end with the spray compartment of the booth, as at the lower end of the apron. The means comprises a series of horizontally spaced plates extending across the chamber and being 15 so constructed and arranged as to provide among them a plurality of upwardly extending tortuous passages for the upward passage therethrough of the fume bearing air, with a novel deflector means, such as a deflector extending across the 20 device, at the top or at the bottom or both, and disposed transversely of the plates and across the openings of the tortuous passages, together with stream projecting means arranged at spaced loci along and opposite the deflecting means for 25 projecting streams of washing fluid thereagainst to scatter the washing fluid into the passages mentioned. The deflector may be V-shaped in cross-section with its ridge or vertex away from the face of the device so that the projected 30 streams may be deflected from both sides of the ridge of the deflector. Also, the deflector may have a plurality of openings with adjacent or otherwise located deflecting elements, for the passage of some of the projected fluid to be scattered into the portions of the tortuous passages 35 opposite the deflector and also for further breaking up the deflected fluid over the deflector to be more extensively scattered. The device may also include a separator located opposite the deflector where the more inactive portions of the 40 tortuous air passages would otherwise be, in which case the deflector may merely have the deflector elements, such as projecting tongues, without the openings or apertures in the deflector as above described, so that such elements 45 will further break up the projected and deflected washing fluid to effect a more distributive scattering thereof.

Another object of the invention is to provide a 50 novel device of the kind described, together with an eliminator which is preferably in spaced relation above the air washing device and serves for eliminating the water or moisture from the air before it passes out to the atmosphere. The 55 eliminator may be of the type disclosed in the copending application of Eric Gustafsson, filed December 1, 1937, under Serial No. 177,563.

An important feature of the invention is the 60 way of distributing the cleaning fluid. The use of atomizing, spraying, and jet projecting nozzles is entirely eliminated. When several small nozzles are used to obtain the required volume of liquid for the desired distribution of the liquid the orifices which are necessarily small plug up 65 or clog thus effecting an improper and inefficient operation of the device, besides requiring frequent shut-downs of the apparatus for cleaning out the holes. Also, there is a tendency to wear out the nozzles, as by erosion, in a very irregular 70 manner, frequently resulting in a total destruction of the nozzles. This condition exists in the usual device because the water jets must be projected under high pressure, and also because the water, which is drawn from the catch basin 75 or receptacle beneath the apron and the washing

chamber, carries some of the particles of the fume material.

In the present invention there are as few stream discharging means as possible and practical, which have larger openings or orifices for 5 the flow therethrough of a comparatively large amount of water, or other liquid, per unit of time, so as to pour over or flood a large area surface at comparatively low pressure. In previous cases the necessary pressures at the nozzles 10 were in the range of from 20 to 30 pounds per square inch, but in the device of the present invention the water pressure runs from about 8 to 15 pounds for the flooding action necessary for 15 washing the air and preventing the adhering of the particles to the surfaces of the device. Also, there is much less power required to circulate the water.

The stream projecting tubes are large and have 20 straight bores with the outlet ends fairly close to the ridge of the deflector plate, so that the stream will impinge the ridge portion of the deflector plate evenly for even deflection of the water on both sides of the ridge. If the outlets were further away the projected stream would spread 25 before impingement with the deflector and evenness of impact and deflection would not be obtained.

The invention also comprehends, when used 30 in connection with a spray booth in the coating art, the provision of novel water distributing means for supplying the water for flushing or flooding the apron, in the form of a curtain, from the means for projecting the streams against 35 the deflectors. At the upper portion of the apron a trough is provided with a discharge opening, such as a slot, adjacent the upper portion of the apron. The stream projecting means also has means for projecting water to or into the trough to supply water for flushing or flooding 40 the apron. The trough has an upwardly extending side wall forwardly spaced from the upper portion of the apron, the latter portion forming the other side wall of the trough, with the former side wall at a higher level than the latter so that 45 streams of water are projected forwardly and upwardly against the forward wall portions of the trough where the water then flows down into the trough and is discharged therefrom to flush or 50 flood the apron. The projecting means has a discharge tube of large capacity and a distributor plate so constructed and arranged as to project the water in a wide fan-shaped sheet or the like for substantially even or uniform distribution of 55 the water throughout the length of the trough.

These curtain water distributors have large 60 capacity discharge tubes with large outlet passages or orifices so that there will be no chance of the material particles carried by the water or other liquid used to adhere to the surfaces of the 65 passages, accumulate and clog them, and the distributor plates are so located as to give a wide spread to the issuing stream so that the water will be uniformly distributed along the whole 70 length of the trough.

Another feature of the invention is the provision 75 of novel plates in the washing device and among which are provided the tortuous air passages. These plates are bent at sharper angles than heretofore so as to increase the total length 80 of the tortuous passage besides also making the course of travel of the air take more abrupt changes or turns whereby there will be a more thorough cleaning of the air both by the increased impingements with the surfaces of the 85

plates and the greater surface contact of the scattered water from the deflectors with the air.

Other objects, advantages, capabilities, features, and the like are comprehended by the invention, as will later appear and as are inherently possessed by the invention.

Referring to the drawings:

Fig. 1 is a front elevational view of a spray booth which may be used in connection with the invention, and showing parts broken away to show the interior construction;

Fig. 2 is a transverse sectional view in a vertical plane of the same with parts shown in side elevation;

Fig. 3 is a fragmentary part sectional and part elevational view of the air washing device and the means for distributing curtain or flushing water for the apron;

Fig. 4 is a similar view taken transversely of the structure shown in Fig. 3;

Fig. 5 is a view similar to Fig. 3 but showing the use of a separator in the air washing device;

Figs. 6 and 7 are elevational views of different forms of separators and deflectors that may be used in lieu of those shown in Fig. 5;

Fig. 8 is a similar view of a separator having more peaked upper and lower ends than shown in Figs. 6 and 7;

Fig. 9 is a fragmentary sectional view on an enlarged scale of a separator and associated deflecting means as shown in Fig. 7;

Figs. 10 and 11 are fragmentary plan views of different forms of deflector plates showing different relations of the deflector elements carried by the plates; and

Fig. 12 is a sectional view on an enlarged scale of a curtain water distributor.

Referring more in detail to the drawings, the embodiments selected to illustrate the invention are shown in connection with a spray booth structure used in the coating art, and which may be made of sheet metal, comprising a booth or compartment 1 having a front opening or door 2, a ceiling 3, a rear wall in the form of an apron 4 over the front face of which may flow a sheet or curtain 5 of water or other liquid from a trough 6 formed between an upwardly extending portion 7 of the apron or rear wall, and a forwardly spaced and upwardly extending wall 8 suitably secured to the lower portion of a front wall 9 of an air uptake later described, the lower end of the wall 8 being so spaced from the upper portion of the apron 4 as to provide an elongated discharge outlet 10 for the trough and adjacent such upper end portion of the apron for discharge of the flushing water, in the form of a sheet or curtain, over the face of the apron. The wall 8 extends up at a higher level than the upper end portion 7 of the apron for a purpose later disclosed.

The lower end of the apron 4 has a downwardly and rearwardly curved portion 11 from which the water flowing down over the apron drops into a receptacle or settling tank 12 located at the lower end of an air uptake 13 having a chamber 14, which tank 12 extends forwardly into the lower rear portion of the compartment 1. The space 15 between the lower end 11 of the apron and the top of the tank or receptacle 12 constitutes a passage between the compartment 1 and the chamber 14 of the air uptake 13 for the passage or flow of air from the former to the latter as shown by the arrows.

An end portion 12a of the receptacle 12 extends out from the side of the structure (see Fig. 1) and

is connected by way of a valved intake 16 to a circulating pump 17 having an outlet or discharge duct 18, which duct is connected to a valved supply pipe 19 and also to a valved connecting pipe 20 leading to a manifold 21. To this manifold 5 are connected pipes 22 and 23 which extend through a side wall of the air uptake 13 and transversely across the chamber 14, the other ends of the pipes 22 and 23 being closed by pipe caps 22a and 23a (Fig. 1). These pipes are vertically spaced for the inclusion therebetween of the air washing device later more fully described, and have spaced stream projecting tubes 24 and 25 for projecting streams of water toward the air washing device, the tubes 24 being directed downward and the tubes 25 being directed upward, as shown.

The air washing device is located between the pipes 22 and 23 and comprises a series of horizontally spaced uprightly disposed angular or bent plates 26 among which are provided upwardly extending tortuous passages 27 through which the uprising fume laden or bearing air passes. This series of plates extends across the chamber 14 from side to side and the plates as an aggregate extend in a transverse direction with the forward and rear ends of the aggregate, respectively resting upon angle brackets 28 and 29 respectively secured to the front and rear walls 30 of the uptake 13, the apron 4 in this case constituting such front wall.

The uptake 13 extends upward to enclose an eliminator chamber 30 in which is disposed an eliminator 31 composed of spaced angular or bent plates similar to those of the cleaning device in the chamber 14, the eliminator being similarly supported on forward and rear angle brackets 32 and 33 respectively secured to the front wall 19 and the rear wall 9 of the chamber portion of the uptake. Extending upwardly from the chamber 30 is a duct 34 leading to the atmosphere or the like. In this duct is provided an exhaust fan 35 driven by a belt 36 operatively connected to a motor 37 mounted on the rear wall or side of the duct 34.

The article to be sprayed is suitably supported in the spraying zone 38 in the booth compartment 1 in such position as to direct the spray from a spray gun appliance 39 normally held in the hand of the operator who generally stands in the doorway 2, or near thereto, of the booth.

Referring to the air cleaner or washer, shown more in detail in Fig. 4, it will be noted that each of the plates 26 comprises vertically spaced upright flanges 40 and 41 and an intermediate acute angular portion 42 extending laterally as shown. The angle of the angular portion is preferably not greater than 60°. Heretofore, such angle has been about 90°. By making the angle less, as about or less than 60°, the altitude of the angular portion is greater and the air path between the plates is thus greatly increased. Also, the passage of air is made to take more abrupt turns. Moreover, the vertical height of the device may also be reduced without shortening the total length of the air passage between the plates.

Above and below the washing device and extending across the upper and lower edges of the plates 26 are located deflector plates 43 and 44, 70 which are preferably V-shaped in cross-section so as to provide ridges or vertices 45 and 46 disposed away from the surfaces, in general, of the device, and with the base edges of the deflector plates engaging the edges of the plates 26, above 75

and below respectively and as shown in Figs. 3 and 4.

The pipes 22 and 23 are in spaced parallel relation with the ridges 45 and 46 respectively, and the stream projecting tubes 24 and 25 extend toward the ridges with the outlets thereof fairly close to the ridges and centered therewith, that is, with the axes of the tubes 24 and 25 intersecting the ridges so that the streams issuing from the tubes will be evenly distributed on both sides of the ridges to be deflected over the inclined faces of the deflector plates. It will be noted that the bores or orifices 47 and 48 (Fig. 3) are comparatively large so as to afford free passage of the water and to prevent accumulation of material particles and the consequent clogging-up of the bores.

Each of the deflector plates is provided with a plurality of deflector elements 49 or 49^a (see also Figs. 10 and 11) which extend outwardly from the inclined surfaces of the plates. These elements may be formed by partial punchings whereby perforations or apertures 50 or 50^a are provided in the plate with the projections 49 or 49^a in the form of outstanding tongues or the like. The holes 50 or 50^a also serve for the passage of water therethrough into the portions of the air passages 27 located opposite the deflector plates.

As the water streams issue from the tubes 24 and 25, they divide equally on the ridges and the stream halves are deflected in widely diverging sheets over both inclined surfaces of each deflector plate. As these sheets of water move rapidly toward the bases of the plates they encounter the deflector elements 49 or 49^a so as to be further deflected in smaller divergent sheets of water so that by the time these numerous sheets of water reach the mouths of the passages 27 and are projected thereinto, the water has been scattered and widely distributed in practically all directions in a more or less uniform amount. In this way, the surfaces of plates 26 receive the water in ample amount over every part and portion of the plates so that there is a thorough and efficient flooding of such surfaces besides thoroughly washing the air passing upwardly in the tortuous passages 27.

In Fig. 10, the deflecting elements 49 are shown as all facing the same way, that is, in parallel, but in Fig. 11 the elements 49^a are disposed at different angles, or, so as to say, facing the tube 24 or 25, as the case may be. When the water sheet passing over the inclined face of the deflector plate encounters these elements, the water streams are resolved into sub-streams flowing from the sides of the deflector elements in diverging sheet-like streams, one at each side of each element as shown in Figs. 10 and 11.

At the same time, some of the water is deflected by each deflector element into the adjacent hole 50 or 50^a to be scattered into the portions of the passages 27 located opposite the deflector plate. However, the deflector plate cuts off a considerable amount of the water that would otherwise enter into such portions of the passages 27, and, therefore, a separator may be interposed between the deflector plates, as shown in Fig. 5.

In the form of device shown in Fig. 5, a separator 51, in the form of a hollow rectangular box, is located in the washing device between the deflector plates 43 and 44, the separator having top and bottom walls 52 and 53, respectively, opposite the plates 43 and 44. In this case the plates

26 do not extend clear across but are shorter and have their inner ends abutting the side walls of the separator 51. Also, the holes in the deflector plate may be omitted or filled, or blanked off, so as not to waste water that would otherwise pass through such holes into the triangular space between the deflector plate and the end wall 52 or 53 of the separator. For the purpose of permitting adjustment of the deflector plate, transversely, it is preferable to have the end walls 52 and 53 flat or so formed as not to interfere with such adjustment.

In Figs. 7 and 9 there is shown an auxiliary V-shaped plate 54 within the deflector plate 43 so as to blank off or block off the holes 50 to 15 prevent passage and wastage of water therethrough, and still the deflector plate with the auxiliary plate may be adjusted as described above.

However, the upper and lower ends or walls of the separator may be peaked to fit flush with the deflector plate. As shown in Fig. 6, the separator 51^a has upper and lower peaked walls 55 and 56 against which the deflector plates 43 and 44 seat.

While the angle of the deflector plate has been shown in most cases as obtuse, such angle may be less obtuse or even acute. Hence, in Fig. 8 the deflector plate 57 is shown much more peaked and of less than 90°.

The water or liquid distributing means for supplying the curtain water comprises curved ducts 58 (see Fig. 12) connected to the pipe 24 and having a water projecting tube 59 provided with a large bore 60 for directing a large diameter stream of liquid upwardly and forwardly toward the wall portion 8 of the trough 6 (Fig. 2). To the outlet end portion of the tube 59 is connected a hub 61 carrying a distributor plate 62 against which the round stream of water impinges and is resolved into a widely diverging sheet of water (see Fig. 4) so that the water will be uniformly distributed along the wall 8 above the trough 6. The water, after impinging the wall 8, then falls into the trough 6 and flows down through the outlet in the bottom of the trough into the form of a curtain of water 5, over the front face of the apron 4 to flush such face.

In operation the fume laden air passes upwardly in the chamber 14 and through the tortuous passages 27 where the air meets a flood of washing liquid whereby the particles are carried down by the water dropping down in the chamber 14 and into the receptacle 12 to settle therein. The water in the tank 12 is circulated by way of the pump 17 to the stream projecting tubes 22 and 23 whence the streams are deflected over the deflecting plates and by the deflecting elements to be resolved into a multiplicity of widely divergent sheet-like streams which pour into the passages 27 and impinge the plates 26 to thoroughly wash the air.

At the same time, liquid is projected by the distributor 58-59-62 also into the form of widely divergent sheet-like streams for impingement against the wall 8 so as to fall into the trough 6 and to flow down over the apron 4, the water eventually returning to the tank 12, thus completing its circuit.

Also the air freed of the fume passes upwardly through the eliminator 31 where the moisture borne by the air is separated out and falls down into the washing device in chamber 14. The term "fume" is used herein generically as comprehending any divided material, whether 75

in the form of dust, or cloud, or the like, and the term "water" is used generically to cover any fluid, such as oil, or any liquid chemical, or an emulsion or colloid, or the like, or even a gaseous fluid or vapor, and the term "booth" is used generically to include any device used in the industrial arts wherein the divided matter is formed or arises as a result or incidental to the particular process being used.

10 While we have herein described and upon the drawings shown a few illustrative embodiments of the invention, it is to be understood that the invention is not limited thereto but comprehends other constructions, details, arrangements 15 of parts, features, and the like without departing from the spirit of the invention.

Having thus disclosed the invention,

We claim:

1. An eliminator for divided material formed 20 during a process in the industrial arts wherein the material is carried by a stream of air passing through the means for carrying out the process; comprising a cleaning chamber in communication with such means, an air cleaning device 25 in said chamber and comprising a series of horizontally spaced plates extending across the chamber and being so constructed and arranged as to provide among them a plurality of upwardly 30 extending tortuous passages for the upward passage therethrough of the material bearing air, a deflector extending over the upper side of said device and transversely across said plates and the upper opening of said passages, a deflector 35 extending along the under side of said device transversely of said plates and across the lower openings of said passages, and fluid stream pro-

jecting means located opposite said upper and lower deflectors for projecting streams of washing fluid downwardly against the upper deflector and upwardly against the lower deflector to distributively scatter the fluid downwardly and upwardly into said passages.

2. An eliminator for divided material formed during a process in the industrial arts wherein the material is carried by a stream of air passing through the means for carrying out the process; comprising a cleaning chamber in communication with such means, an air cleaning device in said chamber and comprising a series of horizontally spaced plates extending across the chamber and being so constructed and arranged as to provide among them a plurality of upwardly extending tortuous passages for the upward passage therethrough of the material bearing air, a deflector extending over the upper side of said device and transversely across said plates and the upper opening of said passages, a deflector extending along the under side of said device transversely of said plates and across the lower openings of said passages, and fluid stream projecting means located opposite said upper and lower deflectors for projecting streams of washing fluid downwardly against the upper deflector and upwardly against the lower deflector to distributively scatter the fluid downwardly and upwardly into said passages, said deflectors being provided with pluralities of spaced deflector elements for further deflecting some of the deflected fluid into a plurality of divergent streams for a distributive scattering of fluid into said tortuous passage.

JOHN F. ROCHE, JR. 35
GEORGE A. HARKER.
